FOLDING IRONING BOARD.

REISSUED

Application filed October 26, 1926. Serial No. 144,282.

The object of the invention is to provide a folding as well as an adjustable ironing board which is so constructed that it can be entirely enclosed, when not in use, in a wall 5 pocket having a depth as shallow as that formed by three inch studding; to provide a device of this character that may be readily extended to and locked in operative position, and when in such position, adjusted 10 laterally and quickly and effectively clamped to most effectively meet the convenience of the operator; and to provide a construction of this sort which will enable the architect, in planning, to arrange the room to better 15 advantage than with the ordinary form of folding ironing board which will usually interfere with adjacent walls, stoves, sinks, breakfast-nooks, cupboards and the like, and obstruct door openings.

20 With this object in view, the invention consists in a construction and combination of parts of which a preferred embodiment is illustrated in the accompanying drawings, wherein:

25 Figure 1 is a side elevational view showing the invention arranged in operative position, the wall pocket being shown in section.

Figure 2 is a view similar to Figure 1 but showing the board in folded position.

30 Figure 3 is a sectional view on the plane indicated by the line 3—3 of Figure 1.

Figure 4 is a sectional view on the plane indicated by the line 4—4 of Figure 1.

Figure 5 is a sectional view on the plane 35 indicated by the line 5—5 of Figure 1.

Figure 6 is a view of the board.

The board 10, when not in use, is adapted to be arranged vertically and disposed within a pocket 11 formed in the wall of the 40 room, the pocket being provided with a closure in the form of a door 12 to cover the board when not in use. Guide grooves 13 are formed in the opposite side walls of the pocket 11 and slidably engaged in these 45 grooves are the slides 14, the latter being formed with openings for the reception of trunnions 15 formed at the remote end of a rocker bar 16. A plate 17 is secured to the rocker bar by means of bolts 18 and on the 50 under face at the end remote from the rocker bar, there is formed in the plate 17 a groove 19, this groove receiving the transverse portion of a stirrup 20, the arms of which at the free ends are outturned, as indicated at

21, to provide gudgeons pivotally engaging 55 sockets formed in the opposite side walls or guides of the pocket 11.

The plate 17 supports the board 10, the latter at the forward end being tapered, as indicated at 22. A bolt 23 extends through the plate 17 and through the board at the apex of the tapered portion, thus providing a pivotal connection between the board and the plate. The plate is also provided with an arcuate slot 24 concentric with the 60 bolt 23 and the board is provided with a bolt 25 extending through the slot 24 and receiving on its upper end a wing nut 26. Obviously, this construction provides for the adjustment of the board laterally with the 65 bolt 23 as a pivot, the bolt 25 serving to clamp the board in adjusted position.

The board 10 engaging the plate 17 on the under face, serves to close the slot 19 and thus pivotal connection between the 70 plate 17 and the stirrup is provided, the stirrup also having pivotal connection with the side walls of the pocket. By means of this arrangement, the board may be extended to horizontal operative position or folded 75 into vertical position within the pocket, merely by respectively elevating the rear end of the board or depressing the plate 17, the slides 14 in this operation moving down into the grooves 13 and the stirrup swinging on 80 its pivotal connections with the pocket and the board until it reaches an approximate vertical position, when the board is disposed in vertical position within the pocket.

The extended or operative horizontal position of the board is maintained by a transverse bar 27 secured transversely of the pocket against the rear wall thereof, this bar overhanging the inner end of the plate 85 in the horizontal position of the board and acting as an abutment stop. The board is thus supported horizontally jointly by the stirrup and the stop 27, the slides preventing any movement of the board longitudinally.

The sleeve board 28 is pivotally secured at 90 its forward end, as indicated at 29, with a transverse rocker bar 30, the latter having trunnions or gudgeons 31 engaged in bearing plates 32 mounted on the side walls of the pocket. The pivotal connection of the board 28 with the rocker bar provides for 95 its being moved laterally just as in the case of the main board, with the exception that 100 105

no means is provided for locking it in different angular positions, as this is unnecessary.

To support the sleeve board when extended, the U-shaped member 33 is provided, this member having inturned extremities 34 engaged in sockets in the opposite side edges of the sleeve board. The U-shaped member bears upon the upper face of the main board 10 when supporting the sleeve board and, when the latter is not in use and arranged in folded position within the pocket, the U-shaped member may be folded down against the under face thereof.

15 The invention having been described, what is claimed as new and useful is:

A folding ironing table comprising a board having a transverse plate with which the board is pivotally connected at its forward end for angular adjustment in a horizontal plane, a rocker bar connected with said plate and provided with trunnions at its extremities, slides with which said trunnions are engaged, guide members having grooves traversed by the slides, and a folding supporting member connected with the plate at a point remote from the rocker bar and having pivotal mountings in the guide members.

20 In testimony whereof he affixes his signature.

STEPHEN F. SLAWSKI.
